UNITED STATES PATENT OFFICE.

WILLIAM C. SPENCER, OF BATAVIA, ILLINOIS.

BOILER-FIUE CUTTER.

1,168,344.

Specification of Letters Patent. Patented Jan. 18, 1916.

Application filed March 25, 1915. Serial No. 16,967.

To all whom it may concern:

Be it known that I, WILLIAM C. SPENCER, a citizen of the United States, and a resident of the city of Batavia, in the county of Kane and State of Illinois, have invented a certain new and useful Improvement in Boiler-Flue Cutters; and I do hereby declare that the following description of my said invention, taken in connection with the accompanying sheet of drawing, forms a full, clear, and exact specification, which will enable others skilled in the art to which it appertains to make and use the same.

My invention relates generally to improvements in boiler flue cutter, and it consists, essentially, in the novel and peculiar combination of parts and details of construction, as hereinafter first fully set forth and described and then pointed out in the claims.

In the drawing already referred to which more fully discloses my invention, Figure 1 is a plan thereof. Fig. 2 is a rear elevation of said invention and Fig. 3 a front elevation thereof. Fig. 4 is a perspective view of a handle employed in connection with my invention, and Fig. 5 is a like view of a detail of construction.

Like parts are indicated by corresponding symbols or characters of reference in all the figures of the drawing.

My invention is designed to facilitate the repair of boilers of the water tube type, such as the Babcock & Wilcox and the like. As is well known these boilers have a plurality of horizontal and vertically inclined, or vertically inclined, or horizontal, or vertical tubes, as the case may be, the ends of which tubes are received in coinciding openings through one wall of the front and rear, or top and bottom headers, and in which openings they are expanded and beaded to create steam and water tight joints in a manner readily comprehended. These headers are in general double walled structures with a water space therebetween, and in the wall opposite that already referred to, are coinciding openings, normally closed by hand hole plates, through which openings access may be had to the interior of the aforesaid tubes for the purpose of cleansing the interior thereof from sediment or scale. And a further purpose of said openings is to permit the passage therethrough of a full length of tubing which has been burned, deflected, distorted or become otherwise damaged in use. It is well understood that in setting up

these boilers several vertical flame deflector walls and the like, generally made from fire brick, are interposed between the front and back or top and bottom headers, and encompassing the water tubes thereof are provided. In the present practice of removing defective tubes, there is provided a small internal cutter to cut said tubes adjacent to their engagement with the walls of the respective headers. Then by physical force applied by crow bars, wedges, and hammer blows, the cut tube is forced through the coinciding opening in the opposite wall of the header in question and likewise through the deflecting walls for its entire length. In the case of a tube which is somewhat deflected or one with a portion of a seam opened apart, or in fact a damaged tube of any sort, this process of removing the tube by driving the same as explained is a tedious and onerous task, as well as an expensive one, it being naturally understood that the spacing of the adjacent water tubes is rather close, so that the physical effort required to drive out the tubes is applied in close and cramped quarters.

The essence of my invention, therefore, is to provide an external cutter which may be applied to and embrace the tube to be removed, and cut the same into as many lengths as necessary to eliminate the burdensome and tiring driving process.

To more fully explain my invention I now refer to the drawing, in which A and A' are substantially like semi-annular members of preferably rectangular cross section, though it is evident that a different contour of cross section may be employed. At one end these members are maintained in spaced apart and pivoted relationship by a link 10 and pintle screws 11 and 12 or analogous means whereby said members are capable of pivotal and likewise of endwise movement with respect to each other, while the opposite ends of said members are maintained in adjustable spaced apart relation by an adjusting stud 13, the head 14 of which engages lips 15 having a vertical slot 15^a of member A' and the opposite threaded end 16 of which is in threaded engagement with a tapped opening 17 passing through an oscillatable threaded pintle 18, which pintle is rotatably mounted in member A in any desired manner; in this case there being a slot 19 for the reception of the threaded portion 16 of the stud 13 and a tapped cross hole 20 in the member A for the threaded engagement therein of the

threaded pintle 18, it being understood that the said pintle is threaded into the opening 20, until the axis of the tapped opening 17 in said pintle coincides with similar axes of the slots 15^a and 19. Said pintle is provided with a depression 21 sunk in the end thereof for application of what is known as a key set screw wrench, or analogous means may be provided, wherewith said pintle may easily be entered into the opening 20. It is to be mentioned that this stud has what may be termed a running fit in said opening, so that no obstruction to partial rotation thereof is presented when it is desired to oscillate the stud 13 to swing its head 14 thereof out of engagement with the lip 15, so that the members A and A' may be freely swung apart in an obvious manner. It will be further noted that the widths of the slots 15^a and 19 are somewhat greater than the diameter of the adjusting stud 13, so that the slight endwise movement of the pintle 20, when said stud is swung away from the lip 15, will cause no friction of the parts.

It is preferred that the members A and A' be formed in the well-known process of founding in steel or tough cast iron, and in this process there are formed in each of these members preferably rectangular radial through passages 25 for the reception of flat-face rollers 26 and V-shaped cutter rollers 27, which are rotatably mounted in said passages on pintles 28, which latter are fixed in position by any preferred media. The radii of the axes of these pintles are so calculated that when the cutters 27 have penetrated through the wall of a pipe, said wall is not yet in impingement with the inner circumference 30 of the member A' adjacent said cutters. I prefer to locate all of the cutting rollers in one of the members and the flattening rollers in the other member, because of the fact that were the rollers alternated, the cutting action of the cutting rollers would be retarded by the flattening rollers. And I do not limit myself to two of each but may employ a larger number, depending entirely upon the pipe to be cut. These passages 25 may be located medially of the facial width of the members A and A' if desired, but I prefer to form the same closer to one side for the reason that near the opposite side I provide a plurality of equally spaced through passages 31, for the reception of the end of a point 32 of a manipulating handle 33, whereby the device may be rotated in a manner easily comprehended.

The operation of my invention may now be described as follows: The adjusting screw 13 is first swung free from the lip 15 and the members A and A' spread apart so as to pass over the tube to be cut, with that side of the members nearest the cutters placed adjacent the header of the boiler, the mem-

bers are then swung together and the adjusting stud applied. Rotative movement to the head 13^a of the adjusting stud is created by a suitable wrench and the device rotated by the handle 33. It will be seen that the cutters 27 will cut a V-shaped groove in the periphery of the pipe, and the burrs raised by such cutters on either side of the groove will be flattened by the rollers 26. This process is continued until the pipe is cut at that point, whereupon the adjusting screw is eased until to sufficiently spread apart the members A and A' so that the device may be slid along the pipe or water tube until another cut is to be made, where the cutting process is repeated. In this manner the pipe may be cut into short lengths, and the heavy driving of the same through obstructing deflection walls and the like is entirely avoided. Moreover, in such short time, and in such short lengths, that the pipes may be flattened and passed into the fire box or to the top of the boiler, by passing them between adjacent tubes, whereby the driving of the short lengths through the openings in headers is eliminated and a great saving of time thereby effected.

I have hereinbefore disclosed the preferred mode of practising my invention, but I reserve the right to make such and any changes as might occur to one skilled in the art to which this invention appertains, or to make any and all such alterations as may be permitted under the doctrine of equivalents.

Having thus fully described my invention I claim as new, and desire to secure to myself by Letters Patent of the United States:—

1. A cutter comprising two semi-annular members maintained in spaced apart relation, cutting rollers rotatable in one of said members and flattening rollers rotatable in the other of said members, a link connecting adjacent ends of said spaced apart semi-annular members, and arranged to permit of pivotal and endwise movement of said members with respect to each other, and adjusting means pivoted to the other end of one of said members and engaging the adjacent end of the other of said members, whereby these ends of said members may be forced toward each other.

2. A cutter comprising two semi-annular members maintained in spaced apart relation, and adapted for free rotation about the periphery of a tube or the like, cutting rollers rotatable in one of said members and flattening rollers rotatable in the other of said members, a link connecting adjacent ends of said spaced apart semi-annular members, and arranged to permit of pivotal and endwise movement of said members with respect to each other, and adjusting means pivoted to the other end of one of

said members and engaging the adjacent end of the other of said members, whereby these ends of said members may be forced toward each other.

- 5 3. An article of the class described comprising two semi-annular members connected together at one end in spaced apart relation and adapted for pivotal and endwise movement with respect to each other and
10 adjustably and releasably connected at the opposite end, and adapted for free rotation about the periphery of a pipe or the like, there being a plurality of radial, equally spaced through openings in said members,
15 cutting and flattening rollers journaled in said openings, and projecting beyond the interior periphery of said members, and pockets in the outer periphery of said members for the reception of a turning wrench.
20 4. In an article of the class described, including two semi-annular members having open slots in adjacent ends thereof, a link located in said slots and pivoted at its ends to said members, whereby said members are
25 maintained in spaced apart relation and are adapted for pivotal and endwise movement with respect to each other, cutting and flattening rollers journaled in said members,

and means adapted to draw the free ends of said members toward each other. 30

5. An article of the class described comprising a pair of semi-annular members entirely free from external projections on the outer periphery thereof, a hinged link located within said members, and pintles connecting said link to said members at opposite ends thereof, there being depressions in the periphery of said members opposite the hinged connection, one of said depressions having an oscillatable pin passing therethrough, said pin having a threaded aperture alined with said depression, the other of said depressions having a slotted shoulder, a headed, threaded stud, the head of which is adapted to bear against said 45 shoulder, and the threaded portion of which is arranged to engage the threaded aperture in said pin, whereby said members may be adjustably and removably connected, and pockets in the periphery of said members 50 for the reception of a turning wrench.

In testimony that I claim the foregoing as my invention, I have hereunto set my hand.

WILLIAM C. SPENCER.
